PATENTED SEPT. 18, 1906.

J. HASSALL.

FRIEZE FOR WALL COVERINGS.

APPLICATION FILED JULY 10, 1906.

Witnesses:

Inventor

By # UNITED STATES PATENT OFFICE.

JOHN HASSALL, OF LONDON, ENGLAND, ASSIGNOR TO LAWRENCE & JELLICOE, LTD., OF LONDON, ENGLAND.

DESIGN FOR A FRIEZE FOR WALL-COVERINGS.

No. 38,246.

Specification for Design.

Patented Sept. 18, 1906.

Application filed July 10, 1906. Serial No. 325,544. Term of patent 7 years.

To all whom it may concern:

Be it known that I, JOHN HASSALL, a subject of the King of Great Britain, residing at 88 Kensington Park road, London, England, have invented a new, original, and ornamental Design for a Frieze for Wall-Coverings, of which the following is a specification.

My design consists of a continuous frieze shown in sections in the accompanying drawing.

I claim—

The ornamental design for a frieze for wall-coverings, as shown.

JOHN HASSALL.
